EYEGLASS LENS DRILLING MACHINE

Augustine T. Roche, Tiffin, Ohio

Application August 9, 1934, Serial No. 739,156

5 Claims. (Cl. 77—19)

My invention concerns machines or devices for drilling holes in eyeglass lenses for the attachment to the lenses of the nose and bow pieces, or parts used in the frameless type of glasses. 5 My object is to provide a machine of simple and compact construction by which such drilling may be done rapidly and efficiently, to the end that the minimum of time shall be required for the operation and with the highest degree of 10 convenience to the optician or operator and without breakage or other damage to the lens. I illustrate in the drawing what I now consider the most complete and satisfactory embodiment of my invention, but it is to be understood that 15 I do not confine the scope of my protection to that particular embodiment thereof, as changes may be made which, though different in form therefrom, will nevertheless embody the principle of my invention.

20 Briefly describing in a preliminary way what is shown in the drawing that embodiment of my invention will be found to comprise, mounted compactly on a portable base, a drill device proper comprising a lens support and a drilling tool, 25 an electric motor for revolving the tool, a drill point grinder or sharpener in the form of an emery wheel or disc and belt-form driving connections between the motor and the drill tool and the grinding disc. It is one of the features of 30 my invention that when the drill tool requires sharpening, it may be detached from its rotating mechanism without stopping the latter and placed in contact with the sharpening disc so that nothing more is required than to withdraw 35 the drill from its rotating means by a simple motion, and then by movement of it but a short distance apply its point to the sharpening disc and then by equally simple and easily performed motions, restore the drill tool to its driving 40 mechanism to resume the drilling operation with the minimum loss of time. Thus drilling and sharpening operations may be performed in such close sequence as in effect to make them a continuous operation so that there is practically no interruption in the drill operation. The embodiment of my invention shown in the drawing will be found to possess other important attributes as will later appear from the detailed description given hereinafter of such embodiment 45 of my invention.

In the drawing:

Fig. 1 is an elevation of such embodiment of my invention;

Fig. 2 is a top plan view thereof;

Fig. 3 is a vertical section through the drilling devices proper.

Fig. 4 is a transverse section in a plane passing vertically through the shaft which carries the grinding or sharpening disc.

Describing in detail what is shown in the drawing, the base 10 is a flat oblong member upon which is mounted near one end an induction motor 11, and upon which at the other end is a standard 12, upon which the drilling devices 10 proper are mounted, and between the motor and said standard is mounted on the base a vertical standard 13 which has a horizontal bearing for the shaft of the sharpening disc.

A drilling member is mounted on the standard 12 and comprises the drill 14 which is a slender cylindrical steel rod with one end sharpened to a point to provide characteristic drill cutting edges and a drill stem 15 having a hand piece or push-head 16 at one end thereof. The drill 14 is secured in the longitudinally extending opening in a cylindrical stem 15 with its cutting end below the bottom of such stem, and to the top of the stem is swivelled a push-head 16, to enable pressure to be applied by the finger of the operator to secure cutting contact of the drill with the lens. The push-head 16 is swivelled because the drill stem is adapted to be rotated at high speed by a tubular spindle 17, between which, and the stem, is a readily separable driving connection to enable the stem with the drill to be removed as I have before explained to enable the sharpening of the drill. The clutch connection shown is simply a radial pin 18 projecting from the side of the drill stem 15 just below the swivelled head 16, and a radial notch 19 in the upper end of the spindle into and out of which the radial pin may be placed.

Secured to the upper end of the spindle 17 is a belt pulley 20 which hereinafter explained, 40 is drivingly connected with the electric motor.

The drill spindle 17 is journaled in a vertical bearing 21 that forms a part of an arm 22 mounted on the standard 12, and the spindle with the drill parts carried thereby is vertically slidable 45 in such bearing to enable the necessary longitudinal movement of the drill in its operation. A coil spring 23 surrounding the spindle and interposed between the underside of the pulley 20, and the top of the bearing 21 yieldingly holds 50 the spindle and the drill parts carried thereby in an elevated position.

Below the drill point a lens support 24 is situated that consists of a vertical metal post in axial alignment of the drill axis and which is 55

firmly supported by a horizontal bracket 25 which projects from the arm 22. Preferably, said post is held in position by a screw 26 which enables whatever vertical adjustment of the post 5 may be found desirable. For a drilling operation, the lens, of course, is held flatwise on the top of the post or support 24, and in order to closely or accurately hold the lens in position against sidewise movement, its peripheral edge 10 is engaged by a gauge 27. The latter is preferably a screw whose threaded shank engages a threaded hole in the arm 22, in order that the outer lens-edge engaging end of the gauge may be closely adjusted to position with reference 15 to the drill. Preferably, the lens-edge engaging surface of the gauge is some material which will not break or chip the contacting parts of the lens and this may be supplied by a fiber plug 28 set in an opening in the outer end of the 20 gauge-forming screw. A set screw 29 is provided to lock the gauge in adjusted position.

The drill 14 is movably and removably secured to the drill stem 15 so that there may be longitudinal adjustment to compensate for wear and so 25 that a new drill may be substituted for one that is no longer useful. It is desirable to enable the necessary movements of the drill and its removal to be done as quickly as possible to avoid waste of time and, I accordingly secure the drill to the 30 stem by means of a cement which, while efficient when cold, upon application of heat to stem will release the drill. The cement I prefer to use, is a wax cement.

The horizontal shaft 30 upon which is mounted 35 the emery disc 31 passes through a brass bushing 32 mounted in the upper end of the standard 13, and upon the side of the standard opposite the emery wheel 31 is affixed to said shaft a grooved driving pulley 33, which by a belt 34 is connected 40 with the driving pulley 35 of the electric motor 11. Alongside the pulley 33 is a smaller belt pulley 36 which by a belt 37 is connected with the spindle pulley 20, and thus the latter and the 45 drill receive motion from the motor by way of the belt connections with the grinding wheel shaft 30. To tighten the belt 34 the electric motor is supported by an arm 38 which is pivoted at one end to a lug 39 by a screw device 40 which is set to secure the desired tension on the belt 34. 50 And to enable the belt 37 to be readily tightened, the spindle carrying arm 22 is connected by a pivot 41 with the standard 12, and an arm-adjusting screw 42, which engages a horizontally threaded hole in the standard 12, and at its inner end 55 bears against a part of arm 22 below its pivot 41 to exert pressure against such arm to swing it in a direction to tighten the belt 37.

For the convenient and accurate support of a drill requiring sharpening, a drill rest is provided in the form of an arm 43 which extends tangentially at a downward incline from a point close to the periphery of the emery wheel and which is mounted upon a vertical standard 44 rising from the base 10 substantially midway 60 between the standards 12 and 13, and thus the drill rest is the minimum distance from the drill spindle so that the removal of the drill for sharpening and its replacement after sharpening may be effected with the minimum amount of movement by the operator and with the minimum loss 65 of time, on account of resharpening of the drill. In Fig. 1, the drill is shown in dotted lines on the rest.

For the easy and convenient lubrication of the 75 emery wheel shaft 30, oil holding packing 45 is

placed in a vertical hole in the top of the standard 13 with the oil screw 46 bearing upon the top thereof, the bushing 32, of course, having in its periphery a hole that aligns with the packing. The bushing 32 may be readily removed for replacement when necessary. 5

Preferably, as a part of the equipment a reamer 47 is provided for reaming the lens hole after it has been drilled. Such reamer is of hard steel and of tapering form with a shape that is angular 10 in cross section providing reaming edges. Such reamer 47 can be removably secured to the emery wheel shaft, as by having a shank at one end thereof thrust into an axial hole in one end of such shaft. The emery wheel provides a ready 15 and advantageous means of sharpening the reamer when necessary. 15

I preferably use an electric motor of the induction type because it assures a uniform speed at 20 all times. And as the motor is supplied with a suitable plug connector my machine is wholly portable as a unit, and may be placed for use in such position as may be most convenient or advantageous. 25

In view of the foregoing description, only a brief explanation of the drilling of a lens is necessary. The operator first marks by hand the places where the holes are to be drilled and then the lens is placed on the lens support 24, and with its edge in contact with the gauge so that the marked spot to be drilled is immediately below the sharpened end of the drill. Then a drop of suitable oil having been applied to the drill end, and with the drill in rapid rotation, the drill is pressed downward by finger pressure on the 35 push-head 16 in order to place the drill in contact with the lens and to feed the drill as cutting proceeds, and at short intervals during the drilling should be lifted from the lens to allow the oil to pass from the surface under the cutting 40 end of the drill. When the hole is cut half way through the lens, the lens should be turned over and accurately positioned for the drilling of the hole from the opposite side until the two holes meet and completion of the hole is effected. Then 45 the reamer is used to ream out the hole.

While, as required by the statute, I have set forth in full detail the machine illustrated in the drawing as an excellent embodiment of my invention, it is to be understood that I do not confine 50 the scope of my protection to a machine having such construction shown and described; and of course, I consider myself entitled to protection for the features of my invention which are applicable to other than lens-drilling machines. 55

In the claims, the term "drill" or "drilling member" contemplates and embraces the drilling element, per se, 14 and the drill stem 15 either as an element separate or separable from the drill 14, per se, or as an integral part thereof. 60

What I claim is:

1. A lens drilling machine comprising a hollow vertical drill spindle, a lens support to and from which said spindle is longitudinally movable, a drill having separable driving connection with 65 said spindle and removable bodily therefrom, a pulley fixed to the drill spindle to receive rotation to rotate the spindle, means yieldingly holding the spindle and drill away from the support comprising a coil spring encircling the spindle, and bearing at one end against said pulley, and a relatively fixed bearing for the other end of the spring, and means for applying feeding pressure to the drill during drilling operation comprising 70 a head adapted for direct application of the fin- 75

gers thereto and situated above the driving connection between the drill and the spindle, the drill being removable from the spindle by upward movement therefrom.

- 5 2. A lens drilling device comprising a lens support, a drill in the form of a slender rod, a vertical hollow spindle situated above the support into and from which the drill is movable by vertical movement and from the lower end of which, 10 the cutting lower end of the drill projects to engage the lens, a vertical bearing arm supporting said drill spindle in which the spindle with the drill is vertically movable to carry the cutting end of the drill towards and from a lens upon said 15 lens support, a driving pulley upon the spindle above said arm, a coil spring around the spindle between the underside of the pulley and the top of said arm, a separable driving connection between the upper end of the spindle and the drill 20 that permits removal of the drill from the spindle, and a pressure-receiving head attached to the drill above such driving connection adapted for direct pressure contact of the fingers.

3. A lens drilling device comprising a lens support, a drill in the form of a slender rod, a vertical hollow spindle situated above the support into and from which the drill is movable by vertical movement and from the lower end of which, the cutting lower end of the drill projects to engage the lens, a vertical bearing arm supporting said drill spindle in which the spindle with the drill is vertically movable to carry the cutting end of the drill towards and from a lens upon said lens support, a driving pulley upon the spindle above said arm, a coil spring around the spindle between the underside of the pulley and the top of said arm, a separable driving connection between the upper end of the spindle and the drill that permits removal of the drill from 35 the spindle, a pressure-receiving head attached to the drill above such driving connection adapted for direct pressure contact of the fingers, a base, 40 a pivotal connection between such base and said

spindle supporting arm, a motor driven pulley on said base, a belt connecting the two pulleys, and means to secure the spindle supporting arm against movement on said pivotal connection, said pivotal connection being at right angles to 5 the direction of pull of belt on the arm.

4. In a lens drilling machine, a support having a bearing opening therein of substantial area, a rotatable hollow spindle slidably mounted in said bearing, means for rotating the spindle, a drilling member slidably mounted in said hollow spindle and extending from the ends of the spindle, said drilling member including a tubular sleeve slidably and fittedly mounted in said spindle and a drilling element, a hand piece mounted in one 10 end of said sleeve, the drilling element being fitted in the other end of the sleeve and made fast thereto by heat plastic material which is normally cool, means for detachably connecting said drilling member with said spindle and which 15 comprises the end of said spindle nearest the hand piece having a notched edge and a fixed projection on said drilling member to releasably extend in said notch.

5. In a lens drilling machine, a support having 20 a bearing opening therein of substantial area, a rotatable spindle slidably mounted in said opening for movement toward and from the work to be operated upon, means for yieldably maintaining said spindle away from the work, means for 25 rotating the spindle, a drilling member mounted on the spindle, a hand piece connected to one end of the drilling member whereby the spindle and drilling member may be manually moved toward the work when the hand piece is depressed, and 30 said drilling member and hand piece being slideable relative to the spindle, and means for detachably connecting the drilling member with the spindle comprising releasable interengaging parts 35 on the spindle and drilling member, said parts 40 being engaged and disengaged by movement of the hand piece.

AUGUSTINE T. ROCHE.
